UNITED STATES PATENT OFFICE.

ELISHA LAFAYETTE WHITE, OF HANDLEY, TEXAS.

LOCK-HOPPLE.

SPECIFICATION forming part of Letters Patent No. 394,669, dated December 18, 1888.

Application filed April 9, 1888. Serial No. 270,027. (No model.)

To all whom it may concern:

Be it known that I, ELISHA LAFAYETTE WHITE, a citizen of the United States, residing at Handley, in the county of Tarrant and State of Texas, have invented a new and useful Improvement in Lock-Hopples, of which the following is a specification.

The invention relates to improvements in hopples for horses, stock, and other domestic animals; and it consists in the construction and novel combination of parts hereinafter described, illustrated in the accompanying drawings, and pointed out in the appended claim.

In the drawings, Figure 1 is a perspective view of a hopple embodying the invention. Fig. 2 is a plan view of the device unlocked and with the leather band removed. Fig. 3 is a plan view of the lock-case with the lid and inner portion removed. Fig. 4 is a transverse section on the line $x-x$, Fig. 3. Fig. 5 is an elevation of the lock-case with only the lid or cover removed. Fig. 6 represents views of different modifications of the recesses in the end of the key, which recesses engage corresponding projections on the journal of the latch-hook in the lock.

Referring to the drawings by letter, A designates the metallic cuff, made in two semi-circular sections, B C, connected by the hinge-joint a . At the free end of the section B is the latch-hook b , designed to engage a similar latch-hook within the cylindrical lock hereinafter described, the said end being made concave at b' on each side of the latch-hook b , to rest against and fit upon the outer surface of said cylindrical lock. The portion of the section C forming the hinge-joint a is provided with an outstanding projection, c , perforated to engage a lap-ring, c' , to which the chain c^2 , connecting the two cuffs, is engaged.

D is a leather band provided with transverse slits d , at suitable distances apart to form the loops d' , which engage over the outside of the sections, the band forming a lining to the metal cuff and protecting the leg of the animal therefrom.

On the free end of the section C is the lock E , having a cylindrical casing, e , provided in

its side with the latch-opening e' , into which the latch-hook b enters.

F is a latch-hook similar to and engaging with the latch-hook b , but journaled in the bottom of the casing e and in the transverse partition f within said casing, one of which journals f' is extended and has its end shaped to engage a corresponding recess in the end of a key, f^2 .

G is a double-armed curved spring, having its flattened end g bolted to the bottom of the casing, and with its middle bent portion, g' , bearing on the back of the latch-hook F and pressing it into engagement with the other latch-hook.

H is a cap-piece fitted into the lock-casing above the partition f , and provided with a central opening, h , that constitutes the key-hole. The said cap and partition are connected to the lock-case by the rivet h' .

I is a lid or cover having a stem, i , that passes through the cap-piece, partition, and bottom of the lock-case at a point opposite the rivet h' , and has its end upset outside the said casing. The said stem depends from the lid, near the edge thereof, so that the lid can be turned on the casing to cover the key-opening h and exclude mud and dirt from the lock.

The stem i has upon it a block, K, having two shoulders, k k' . These shoulders bear against the outer arm of the spring G , and retain the lid respectively in its open and closed positions. The end of the journal f' is engaged by the recessed key f^2 , and the latch-hook E turned thereby and disengaged from the latch-hook b . The spring G causes the latch-hook E to engage the latter latch-hook.

There are two of the described devices connected by the chain c^2 . They may be put on the two front legs, the two hind legs, or one front and one hind leg of an animal.

Having described my invention, I claim—
In a hopple, the combination of the semi-circular section B, provided at its free end with the latch-hook b and concave edge b' , and the semicircular section C, provided with the perforated projection c for the attachment of the lap-ring c' , and with the lock E , 100

comprising the cylindrical casing *e*, the partition *f*, the cap-piece *H*, having the central key-opening, the journaled latch-hook *F*, having the end of its journal *f'* formed to fit in 5 the recess in the end of a key, *f²*, the curved double-arm spring, the lid *I*, and the lid-stem *i*, having upon it a block, *K*, provided with the shoulders *k k'*, substantially as and for the purpose specified.

In testimony that I claim the foregoing as 10 my own I have hereto affixed my signature in presence of two witnesses.

EELISHA LAFAYETTE WHITE.
